ABSTRACT

The present invention relates to a lighting device with switchable day/night illumination mode, comprising: a main controlling unit, a driving unit, a lighting unit, a light filtering unit, an illumination mode switching unit, and a power management unit, wherein the lighting unit is coupled to the driving unit and has a plurality of light-emitting devices. Moreover, the main controlling unit is used for controlling the driving unit, so as to drive the lighting unit output a visible light. In addition, the illumination mode switching unit is used for controlling the light filtering unit to show and cover the light-emitting surface of the lighting unit, so as to filter the visible light and make the visible light become a visible light with a specific wavelength; wherein the visible light with specific wavelength causes the smallest excitation to human sympathetic. Thus, using the visible light with specific wavelength as illumination light at night can not only assist users in reading, but also avoid from exciting users' sympathetic and causing melatonin suppression.

LIGHTING DEVICE WITH SWITCHABLE DAY/NIGHT ILLUMINATION MODE**CROSS-REFERENCE TO RELATED APPLICATION**

This application claims foreign priority from a Taiwan Patent Application, Ser. No. 100120922, filed on Jun. 15, 2011.

BACKGROUND OF THE INVENTION**1. Technical Field**

The present invention relates to a lighting device, and more particularly, to a lighting device with switchable day/night illumination mode, capable of outputting a visible light at day and outputting a visible light with a specific wavelength at night, respectively.

2. Description of Related Art

Melatonin is secreted by a gland of Pineal body in human brain, and it has the following influences on physiological functions of human: (1) promoting sleep; (2) affecting emotion; (3) sexual maturity and reproduction; and (4) affecting the immune functions.

Moreover, Researches have been found that the production and the secretion of melatonin are mainly influenced by the following three factors: (A) light: light is transmitted to hypothalamus through retinal nerves, and then transmitted to pineal body through the sympathetic nerves, so as to inhibit the secretion of melatonin, therefore the secretion of melatonin can be inhibited in higher level under the darker environment; (B) circadian rhythm: hypothalamus, like a biological clock, can affect the secretion of melatonin, so that the concentration of melatonin secreted by pineal body has a significant variation according to circadian rhythm, and the concentration of melatonin in blood in the night is 6 times higher than that in the day according to researches; and (C) electromagnetic wave: an electromagnetic wave can not only inhibit the ability of pineal body for synthesizing melatonin, but also inhibit the activity of the synthesis of melatonin.

Light is indispensable in daily life. The light perceptible by human eyes is called visible light, wherein the major natural light is sunlight, and the artificial light has various kinds, such as candlelight, incandescent lamps, fluorescent lamps, LED lamp, OLED lamps, etc. Generally speaking, the wavelength range of the visible light is about 450 nm to 750 nm; the color components of the visible light include red, orange, yellow, green, blue, purple, etc.

Besides, researchers also found that melatonin has the highest sensitivity and the second highest sensitivity under the purple light and the blue light, respectively; therefore, generally, the purple light is not directly used as the artificial light for human beings, but the blue light and the red light are often mixed and then be used as the artificial white light. Thus the lighting devices for emitting the white light, such as an incandescent lamp, an LED lamp and an OLED lamp, all of them contain the blue light component. However, it knows that melatonin has high sensitivity to blue the light, thus, if human body is exposed under the blue light for a long period, the phenomenon of melatonin suppression might be induced, and furthermore, insomnia and mood disorders could also be induced. Based on the above reasons, it is able to know that, when during night, it should better for not using any light sources, such that the light can be avoid from being transmitted to hypothalamus through retinal nerves and transmitted to pineal body through the sympathetic nerves, so that, it would not inhibit the secretion of melatonin.

2

However, for some people having reading habit before bedtime, the artificial light can not be avoided from using to assist people in reading. Although there are sold a variety of night lamps and reading lamps in the market, the light outputted from the night lamps or the reading lamps still includes the short-wavelength light component which will excites people sympathetic. However, researches have been found that, under the condition of one lumen, the orange light having 617 nm wavelength causes the smallest excitation to people sympathetic at night. Accordingly, for the people having reading habit before bedtime, they can adapted the orange light having 617 nm wavelength as the illumination light for reading, so that, they can not only obtain the illumination light for assisting in reading, but also avoid from exciting their sympathetic and causing melatonin suppression.

So that, in view of the sold night lamps and reading lamps are not suitable for using to assist people in reading, the inventor of the present application has made great efforts to make inventive research thereon and eventually provided lighting device with switchable day/night illumination mode.

BRIEF SUMMARY OF THE INVENTION

The primary objective of the present invention is to provide a lighting device with switchable day/night illumination mode, in which, a light filtering unit is used to cover the light-emitting surface of a lighting unit, so that, when the lighting unit outputs a visible light, the light filtering unit would filter the visible light and make the visible light become a visible light with a specific wavelength, wherein the visible light with specific wavelength causes the smallest excitation to human sympathetic; Therefore, using the visible light with specific wavelength as illumination light when night can not only assist users in reading, but also avoid from exciting users' sympathetic and causing melatonin suppression.

Accordingly, to achieve the abovementioned primary objective of the present invention, the inventor proposes a lighting device with switchable day/night illumination mode, comprising:

a main controlling unit;

a driving unit, coupled to the main controlling unit;

a lighting unit, coupled to the driving unit and has a plurality of light-emitting devices, wherein the main controlling unit can control the driving unit to drive the lighting unit, so as to output a visible light;

a light filtering unit, disposed over a light-emitting surface of the lighting unit, used for filtering the visible light and making the visible light become a visible light with a specific wavelength;

an illumination mode switching unit, coupled to the main controlling unit, wherein the illumination mode switching unit is used for controlling and switching the light filtering unit, so that the light filtering unit shows and covers the light-emitting surface of the lighting unit, and then the visible light outputted from the lighting unit is filtered by the light filtering unit and becomes the visible light with the specific wavelength; Moreover, the illumination mode switching unit is able to control and switch the light filtering unit, such that the light filtering unit is withdrawn and stops covering the light-emitting surface of the lighting unit, and then the lighting unit outputs the visible light; and

a power management unit, coupled to the main controlling unit for providing the power to the main controlling unit.

The second objective of the present invention is to provide a lighting device with switchable day/night illumination mode, in which, a light converting unit is used to cover the

light-emitting surface of a lighting unit, so that, when the lighting unit outputs a visible light, the light filtering unit would convert the visible light to a visible light with a specific wavelength, wherein the visible light with specific wavelength causes the smallest excitation to human sympathetic; Therefore, using the visible light with specific wavelength as illumination light when night can not only assist users in reading, but also avoid from exciting users' sympathetic and causing melatonin suppression.

Thus, to achieve the abovementioned second objective of the present invention, the inventor proposes a lighting device with switchable day/night illumination mode, comprising:

- 5 a main controlling unit;
- a driving unit, coupled to the main controlling unit;
- a lighting unit, coupled to the driving unit and having a plurality of light-emitting devices, wherein the main controlling unit can control the driving unit to drive the lighting unit, so as to output a visible light;
- 10 a light converting unit, disposed over a light-emitting surface of the lighting unit, used for converting the visible light to a visible light with a specific wavelength;

15 an illumination mode switching unit, coupled to the main controlling unit, wherein the illumination mode switching unit is used for controlling and switching the light converting unit, so that the light converting unit shows and covers the light-emitting surface of the lighting unit, and then the visible light outputted from the lighting unit is converted by the light converting unit and becomes the visible light with the specific wavelength; Moreover, the illumination mode switching unit is able to control and switch the light converting unit, such that the light converting unit is withdrawn and stops covering the light-emitting surface of the lighting unit, and then the lighting unit outputs the visible light; and

20 a power management unit, coupled to the main controlling unit for providing the power to the main controlling unit.

The third objective of the present invention is to provide a lighting device with switchable day/night illumination mode, in which, a switching unit is used for switching when the lighting unit emits a visible light, such that the number of the light-emitting devices used for emitting light is able to be adjusted and the light-emitting devices in the plurality of light-emitting devices 131b capable of emitting a visible light with a specific wavelength can be controlled to emit light. Therefore, using the visible light with specific wavelength as illumination light at night can not only assist users in reading, but also avoid from exciting users' sympathetic and causing melatonin suppression.

Thus, to achieve the abovementioned third objective of the present invention, the inventor proposes a lighting device with switchable day/night illumination mode, comprising:

- 25 a main controlling unit;
- a driving unit, coupled to the main controlling unit;
- a lighting unit, coupled to the driving unit and has a plurality of light-emitting devices, wherein the main controlling unit can control the driving unit to drive the lighting unit, so as to output a visible light;

30 a first switching unit, coupled to the main controlling unit, wherein when the driving unit drives the lighting unit to output the visible light, the first switching unit may be used for controlling and adjusting the number of the light-emitting devices used for emitting light, or controlling the some light-emitting devices in the plurality of light-emitting devices capable of emitting a visible light with a specific wavelength to emit light and controlling the some light-emitting devices in the plurality of light-emitting devices can not emit the visible light with a specific wavelength not to emit light; and

35 a power management unit, being coupled to the main controlling unit for providing the power to the main controlling unit.

5 BRIEF DESCRIPTION OF THE SEVERAL VIEWS OF THE DRAWINGS

The invention as well as a preferred mode of use and advantages thereof will be best understood by referring to the following detailed description of an illustrative embodiment in conjunction with the accompanying drawings, wherein:

40 FIG. 1A is a first framework view of a first embodiment of a lighting device with switchable day/night illumination mode according to the present invention;

45 FIG. 1B is a second framework view of the first embodiment of the lighting device with switchable day/night illumination mode according to the present invention;

50 FIG. 2A and FIG. 2B are an exemplary embodiment for a desk lamp of lighting device with switchable day/night illumination mode according to the present invention;

55 FIG. 3A and FIG. 3B are an exemplary embodiment for a chandelier of the lighting device with switchable day/night illumination mode according to the present invention;

60 FIG. 4A is a first framework view of a second embodiment of the lighting device with switchable day/night illumination mode according to the present invention;

65 FIG. 4B is a second framework view of the second embodiment of the lighting device with switchable day/night illumination mode according to the present invention;

70 FIG. 5 is a framework view of a third embodiment of the lighting device with switchable day/night illumination mode according to the present invention;

75 FIG. 6 is an exemplary embodiment for a display device of the lighting device with switchable day/night illumination mode according to the present invention; and

80 FIG. 7 is a framework view of a fourth embodiment of the lighting device with switchable day/night illumination mode according to the present invention.

40 DETAILED DESCRIPTION OF THE INVENTION

To more clearly describe a lighting device with switchable day/night illumination mode according to the present invention, embodiments of the present invention will be described in detail with reference to the attached drawings hereinafter.

85 Please refer to FIG. 1A, which illustrates a first framework view of a first embodiment of a lighting device with switchable day/night illumination mode 1 includes: a main controlling unit 11, a driving unit 12, a lighting unit 13, a light filtering unit 14, an illumination mode switching unit 15, a power management unit 16, a switching unit 17, and a sensor unit 18, wherein the driving unit 12 is coupled to the main controlling unit 11, and the lighting unit 13 is coupled to the driving unit 12 and has a plurality of light-emitting devices 131. In the first embodiment of the lighting device with switchable day/night illumination mode 1, it can use bulbs, fluorescent lamps, LED chips, or OLED chips as the light-emitting devices 131, in addition, the main controlling unit 11 is able to control the driving unit 12, such that the driving unit 12 drives the light-emitting devices 131 of the lighting unit 13 to emit light, and then the lighting unit 13 output a visible light.

90 Continuously referring to FIG. 1A, the light filtering unit 14 is disposed over a light-emitting surface of the lighting unit 13, used for filtering the visible light and making the visible light become a visible light with a specific wavelength. The

illumination mode switching unit **15** is also coupled to the main controlling unit **11**, used for controlling and switching the light filtering unit **14**, so that the light filtering unit **14** shows and covers the light-emitting surface of the lighting unit **13**, and the visible light outputted from the lighting unit **13** is filtered by the light filtering unit **14**, so as to become the visible light with the specific wavelength. Moreover, the illumination mode switching unit **15** is able to control and switch the light filtering unit **14**, such that the light filtering unit **14** is withdrawn and stops covering the light-emitting surface of the lighting unit **13**, and then the lighting unit **13** outputs the normal visible light. Herein, it must to explain that, since the orange light having 617 nm wavelength causes the smallest excitation to human sympathetic; thus, preferably, in the first embodiment of the lighting device with switchable day/night illumination mode **1**, the visible light with the specific wavelength is that an orange light having 617 nm wavelength.

The power management unit **16** is coupled to the main controlling unit **11** for providing the power to the main controlling unit **11**, and the switching unit **17** is coupled to the power management unit **16** for switching the power management unit **16** ON/OFF, wherein when the power management unit **16** is turn OFF, the lighting unit **13** stops outputting the visible light. In addition, the sensor unit **18** is coupled to the main controlling unit **11** and the power management unit **16**, used for detecting the light intensity of an external environment. When night is coming, the sensor unit **18** would output a first switch signal to the main controlling unit **11**, and the main controlling unit **11** would control the illumination mode switching unit **15** to switch the light filtering unit **14** to show and cover the light-emitting surface of the lighting unit **13**. Moreover, when day is coming, the sensor unit **18** would output a second switch signal to the main controlling unit **11**, and the main controlling unit **11** would control the illumination mode switching unit **15** to switch the light filtering unit **14** to withdraw for stopping covering the light-emitting surface of the lighting unit **13**.

Furthermore, please refer to FIG. 1B, which illustrates a second framework view of the first embodiment of the lighting device with switchable day/night illumination mode according to the present invention. For the first embodiment of the lighting device with switchable day/night illumination mode, as shown in FIG. 1B, it further includes an activating unit **19**, which is coupled to the sensor unit **18** for activating the sensor unit **18** to detect the light intensity of the environment.

Thus, through above descriptions, the basic framework of the lighting device with switchable day/night illumination mode of the present invention has been completely introduced and disclosed. Besides, for more clearly describing the lighting device with switchable day/night illumination mode of the present invention, it will further introduce the lighting device through exemplary embodiments. Please continuously refer to FIG. 1A and FIG. 1B, and simultaneously referring to FIG. 2A and FIG. 2B, there are shown an exemplary embodiment for a desk lamp of lighting device with switchable day/night illumination mode according to the present invention. As shown in FIG. 2A, the plurality of light-emitting devices **131** of the lighting unit **13** are disposed in a lampshade **31** of a desk lamp, and the sensor unit **18** is equipped on the front end of the lampshade **31** for detecting the light intensity of the environment. In addition, the main controlling unit **11**, the driving unit **12** and the power management unit **16** are implemented on a substrate **1A**, wherein the substrate **1A** is disposed inside a base **32** of the desk lamp **3**. The illumination mode switching unit **15**, the activating unit **19** and the

switching unit **17** are disposed on the top surface and the side surface of the base **32**, respectively.

As shown in FIG. 2B, After a user presses the illumination mode switching unit **15**, the light filtering unit **14** shows and covers the light-emitting surface of the lighting unit **13**, and then the lighting unit **13** outputs the visible light with the specific wavelength, i.e., the orange light having 617 nm wavelength. Meanwhile, when the user presses the illumination mode switching unit **15** again, the light filtering unit **14** is withdrawn and stops covering the light-emitting surface of the lighting unit **13**, such that the lighting unit **13** outputs the normal visible light.

Similarly, as shown in FIG. 2B, when the user presses the activating unit **19** for activating the sensor unit **18** to continuously detect the light intensity of the environment until the night comes, the sensor unit **18** would output the first switch signal to the main controlling unit **11**, and the main controlling unit **11** would control the illumination mode switching unit **15** to switch the light filtering unit **14** to show and cover the light-emitting surface of the lighting unit **13**. Moreover, when the day comes, the sensor unit **18** would output the second switch signal to the main controlling unit **11**, and the main controlling unit **11** would control the illumination mode switching unit **15** to switch the light filtering unit **14** to withdraw for stopping covering the light-emitting surface of the lighting unit **13**.

Please continuously refer to FIG. 3A and FIG. 3B, there are shown an exemplary embodiment for a chandelier of the lighting device with switchable day/night illumination mode according to the present invention. As shown in FIG. 3A, the lighting device with switchable day/night illumination mode of the present invention is practice to a chandelier **4**, in which, the plurality of light-emitting devices **131** of the lighting unit **13** are disposed inside a housing **41** of the chandelier **4**, and the sensor unit **18** is equipped on the front end of the housing **41**, used for used for detecting the light intensity of the environment. In addition, the main controlling unit **11**, the driving unit **12** and the power management unit **16** are disposed in an operation interface **5**; the illumination mode switching unit **15** and the switching unit **17** are disposed on the surface of the operation interface **5**, respectively.

The same to the exemplary embodiment of the desk lamp, in the exemplary embodiment of the chandelier **4**, as shown in FIG. 3B, after a user presses the illumination mode switching unit **15**, the light filtering unit **14** shows and covers the light-emitting surface of the lighting unit **13**, and then the lighting unit **13** outputs the visible light with the specific wavelength, i.e., the orange light having 617 nm wavelength. Meanwhile, when the user presses the illumination mode switching unit **15** again, the light filtering unit **14** is withdrawn and stops covering the light-emitting surface of the lighting unit **13**, such that the lighting unit **13** outputs the normal visible light. Besides, when the user presses the activating unit **19** for activating the sensor unit **18** to continuously detect the light intensity of the environment until the night comes, the sensor unit **18** would output the first switch signal to the main controlling unit **11**, and the main controlling unit **11** would control the illumination mode switching unit **15** to switch the light filtering unit **14** to show and cover the light-emitting surface of the lighting unit **13**. Moreover, when the day comes, the sensor unit **18** would output the second switch signal to the main controlling unit **11**, and the main controlling unit **11** would control the illumination mode switching unit **15** to switch the light filtering unit **14** to withdraw for stopping covering the light-emitting surface of the lighting unit **13**.

Please refer to FIG. 1B again, in the first embodiment of the lighting device with switchable day/night illumination mode, it can further include a brightness switching unit 1A, which is coupled to the main controlling unit 11, wherein when the driving unit 12 drives the lighting unit 13 to output the visible light, the brightness switching unit 1A may be used for adjusting the intensity of the visible light outputted by the lighting unit 13. Thus, for some people having reading habit before bedtime, they can use the visible light with low intensity for assist in reading, so that, they can avoid from exciting their sympathetic and causing melatonin suppression.

The present invention further includes a second embodiment for introducing the lighting device with switchable day/night illumination mode. Please refer to FIG. 4A, which illustrates a first framework view of a second embodiment of the lighting device with switchable day/night illumination mode according to the present invention. In the second embodiment, as shown in FIG. 4A, the lighting device with switchable day/night illumination mode 1 includes: a main controlling unit 11a, a driving unit 12a, a lighting unit 13a, a light converting unit 14a, an illumination mode switching unit 15a, a power management unit 16a, a switching unit 17a, and a sensor unit 18a, wherein the driving unit 12a is coupled to the main controlling unit 11a, and the lighting unit 13a is coupled to the driving unit 12a and has a plurality of light-emitting devices 131a. In the second embodiment of the lighting device with switchable day/night illumination mode 1, the main controlling unit 11a is able to control the driving unit 12a, such that the driving unit 12a drives the light-emitting devices 131a of the lighting unit 13a to emit light, and then the lighting unit 13a outputs a visible light.

Referring to FIG. 4A again, the light converting unit 14a is disposed over a light-emitting surface of the lighting unit 13a, used for converting the visible light to a visible light with a specific wavelength. The illumination mode switching unit 15a is also coupled to the main controlling unit 11a, wherein the illumination mode switching unit 15a is used for controlling and switching the light converting unit 14a, so that the light converting unit 14a shows and covers the light-emitting surface of the lighting unit 13a, and then the visible light outputted from the lighting unit 13a is converted by the light converting unit 14a and becomes the visible light with the specific wavelength; Moreover, the illumination mode switching unit 15a can control and switch the light converting unit 14a, such that the light converting unit 14a is withdrawn and stops covering the light-emitting surface of the lighting unit 13a, and then the lighting unit 13a outputs the visible light.

The switching unit 17a is coupled to the power management unit 16a for switching the power management unit 16a ON/OFF, wherein when the power management unit 16a is turned OFF, the lighting unit 13a stops outputting the visible light. In addition, the sensor unit 18a is coupled to the main controlling unit 11a and the power management unit 16a, used for detecting the light intensity of an external environment. When night is coming, the sensor unit 18a would output a first switch signal to the main controlling unit 11a, and the main controlling unit 11a would control the illumination mode switching unit 15a to switch the light filtering unit 14a to show and cover the light-emitting surface of the lighting unit 13a; Moreover, when day is coming, the sensor unit 18a would output a second switch signal to the main controlling unit 11a, and the main controlling unit 11a would control the illumination mode switching unit 15a to switch the light filtering unit 14a to withdraw for stopping covering the light-emitting surface of the lighting unit 13a.

Moreover, the same to the aforesaid first embodiment, the second embodiment of the lighting device with switchable day/night illumination mode can further include an activating unit. Please refer to FIG. 4B, which illustrates a second framework view of the second embodiment of the lighting device with switchable day/night illumination mode according to the present invention. For the second embodiment of the lighting device with switchable day/night illumination mode 1, as shown in FIG. 4B, it further includes an activating unit 19a, coupled to the sensor unit 18a for activating the sensor unit 18a to detect the light intensity of the environment.

Thus, through above descriptions, the second embodiment of the lighting device with switchable day/night illumination mode has been clearly introduced and disclosed. Besides, the same to aforesaid first embodiment, the second embodiment of the lighting device with switchable day/night illumination mode can also be practice to an exemplary desk lamp (shown in FIG. 2A and FIG. 2B) and an exemplary chandelier (shown in FIG. 3A and FIG. 3B). Moreover, please refer to FIG. 4B again, in the second embodiment of the lighting device with switchable day/night illumination mode, it can further include a brightness switching unit 1Aa, which is coupled to the main controlling unit 11a, wherein when the driving unit 12a drives the lighting unit 13a to output the visible light, the brightness switching unit 1Aa may be used for adjusting the intensity of the visible light outputted by the lighting unit 13a. Thus, for some people having reading habit before bedtime, they can use the visible light with low intensity for assist in reading, so that, they can avoid from exciting their sympathetic and causing melatonin suppression.

Besides, the present invention further includes a third embodiment for introducing the lighting device with switchable day/night illumination mode. Please refer to FIG. 5, which illustrates a framework view of a third embodiment of the lighting device with switchable day/night illumination mode according to the present invention. In the second embodiment, as shown in FIG. 5, the third embodiment of the lighting device with switchable day/night illumination mode includes: a main controlling unit 11b, a driving unit 12b, a lighting unit 13b, a first switching unit 15b, a power management unit 16b, a switching unit 17b, a sensor unit 19b, and an activating unit 1Ab.

Continuously referring to FIG. 5, and simultaneously referring to FIG. 6, which illustrates an exemplary embodiment for a display device of the lighting device with switchable day/night illumination mode according to the present invention. A notebook 2 is shown in FIG. 6 and the lighting device 1 with switchable day/night illumination mode of the present invention is applied as a display device 21 of the notebook 2. More clearly to say, the lighting device 1 with switchable day/night illumination mode of the present invention is applied as an LED display device or an OLED display device.

In the display device 21, the driving unit 12b is coupled to the main controlling unit 11b (the driving unit 12b and the main controlling unit 11b are not shown in FIG. 6). The lighting unit 13b is coupled to the driving unit 12b and has a plurality of light-emitting devices 131b (the lighting unit 13b and the plurality of light-emitting devices 131b are not shown in FIG. 6), wherein the light-emitting device 131b can be an OLED chip or an LED chip. The first switching unit 15b is coupled to the main controlling unit 11b, wherein when the driving unit 12b drives the lighting unit 13b to output the visible light, the first switching unit 15b can switch and adjust the number of the light-emitting devices 131b to emit light, or control the some light-emitting devices in the plurality of

light-emitting devices **131b** capable of emitting a visible light with a specific wavelength to emit light and control the some light-emitting devices in the plurality of light-emitting devices **131b** cannot emit the visible light with a specific wavelength not to emit light. Thus, when night is coming, the user can make the lighting unit **13b** output the visible light with the specific wavelength ranging from 597 nm to 637 nm, or furthermore, output the visible light with 617 nm wavelength (i.e., the orange light).

Moreover, after the activating unit **1Ab** activates the sensor unit **19b** to detect the light intensity of the environment, the sensor unit **19b** would output a first switch signal to the main controlling unit **11b** when night is coming, and the main controlling unit **11b** would control the first switching unit **15b** to switch and adjust the number of the light-emitting devices **131b** used for emitting light, or control the some light-emitting devices in the plurality of light-emitting devices **131b** capable of emitting the visible light with the specific wavelength to emit light and control the some light-emitting devices in the plurality of light-emitting devices **131b** can not emit the visible light with the specific wavelength not to emit light.

General speaking, LED (OLED) display device includes a plurality of red LED (OLED) chips, a plurality of blue LED (OLED) chips and a plurality of green LED (OLED) chips, so that, for the lighting device **1** with switchable day/night illumination mode applied as the display device **21**, the user can control the first switching unit **15b** to switch and control the blue LED (OLED) chips not to emit light, thus, when the driving unit **12b** drives the light unit **13b** to output the visible light, the red LED (OLED) chips and the green LED (OLED) chips would emit the visible light with the specific wavelength ranging from 597 nm to 637 nm.

In addition, for making the lighting unit **13b** able to emit the orange light having 617 nm wavelength, a plurality of orange LED (OLED) chips can be added into the lighting unit **13b**; Therefore, when night is coming, the user can control the first switching unit **15b** to switch and control the red LED (OLED) chips, the blue LED (OLED) chips and green blue LED (OLED) chips not to emit light, thus, when the driving unit **12b** drives the light unit **13b** to output the visible light, the orange LED (OLED) chips would emit orange light with 617 nm wavelength. Moreover, it must to note that, in addition to the display device **21** of the notebook **2**, the lighting device **1** with switchable day/night illumination mode of the present invention can also be applied as the display device **21** of an LCD TV, an LCD display, a smart phone, a multimedia player, and an e-book.

The present invention further includes a fourth embodiment for introducing the lighting device with switchable day/night illumination mode. Please refer to FIG. 7, which illustrates the framework view of a fourth embodiment of the lighting device with switchable day/night illumination mode according to the present invention. In the fourth embodiment, as shown in FIG. 7, the lighting device with switchable day/night illumination mode **1** includes: a main controlling unit **11b**, a driving unit **12b**, a light unit **13b**, a first switching unit **15b**, a power management unit **16b**, a switching unit **17b**, and a second switching unit **18b**, in which, the main controlling unit **11b**, the driving unit **12b**, the light unit **13b**, the first switching unit **15b**, the power management unit **16b**, and the switching unit **17b** in the fourth embodiment are the same to the main controlling unit **11b**, the driving unit **12b**, the light unit **13b**, the first switching unit **15b**, the power management unit **16b**, and the switching unit **17b** in the aforesaid third embodiment.

Different from the third embodiment, in the fourth embodiment, the lighting device with switchable day/night illumination mode **1** further includes the second switching unit **18b**, which is coupled to the main controlling unit **11b**, wherein when the driving unit **12b** drives the lighting unit **13b** to output the visible light, the second switching unit **18b** may be used for adjusting the intensity of the visible light outputted by the lighting unit **13b**. Especially, since modern people popularly use the e-book as a reading device, for instance, iPAD®, so that, for some people having reading habit before bedtime, they can use the second switching unit **18b** to adjust the intensity of the visible light outputted by the lighting unit **13b** and use visible light with low intensity for assist in reading, so that, they can avoid from exciting their sympathetic and causing melatonin suppression. Of course, they also can utilize the sensor unit **19b** to detect the light intensity of the environment, so as to determine whether adjust the intensity of the visible light outputted by the lighting unit **13b** by the second switching unit **18b**.

Therefore, the lighting device with switchable day/night illumination mode of the present invention has been disclosed completely and clearly through the above description. In summary, the present invention has the following advantages:

1. In the first embodiment of the present invention, a light filtering unit is used to cover the light-emitting surface of a lighting unit, so that, when the lighting unit outputs a visible light, the light filtering unit would filter the visible light and make the visible light become a visible light with a specific wavelength, i.e., the orange light having 617 nm wavelength, wherein the orange light causes the smallest excitation to human sympathetic; Therefore, using the orange light as illumination light when night can not only assist users in reading, but also avoid from exciting users' sympathetic and causing melatonin suppression.
2. Inheriting to above point 1, for the first embodiment of the present invention, it further includes an illumination mode switching unit, used for controlling and switching the light filtering unit, so that the light filtering unit shows and covers the light-emitting surface of the lighting unit, and then the visible light outputted from the lighting unit is filtered by the light filtering unit and becomes the visible light with the specific wavelength; Moreover, the illumination mode switching unit can control and switch the light filtering unit, such that the light filtering unit is withdrawn and stops covering the light-emitting surface of the lighting unit, and then the lighting unit outputs the normal visible light.
3. Moreover, for the first embodiment of the present invention, it further includes sensor unit, used for detecting the light intensity of the external environment, wherein when night is coming, the sensor unit **18** would output a first switch signal to the main controlling unit, and the main controlling unit would control the illumination mode switching unit to switch the light filtering unit to show and cover the light-emitting surface of the lighting unit; moreover, when day is coming, the sensor unit would output a second switch signal to the main controlling unit, and the main controlling unit would control the illumination mode switching unit to switch the light filtering unit to withdraw for stopping covering the light-emitting surface of the lighting unit.
4. In the second embodiment of the present invention, a light converting unit is used to cover the light-emitting surface of a lighting unit, so that, when the lighting unit outputs a visible light, the light converting unit would convert the visible light to a visible light with a specific

11

wavelength, i.e., the orange light having 617 nm wavelength, wherein the orange light causes the smallest excitation to human sympathetic; Therefore, using the orange light as illumination light when night can not only assist users in reading, but also avoid from exciting users' sympathetic and causing melatonin suppression.

5. Inheriting to above points 2, 3 and 4, for the first embodiment of the present invention, it also includes an illumination mode switching unit and a sensor unit.

6. In addition to be applied as a display device of a notebook, the lighting device with switchable day/night illumination mode of the present invention can also be applied as the display device of an LCD TV, an LCD display, a smart phone, a multimedia player, and an e-book, so that, when night is coming, the user can control the first switching unit to switch and control the blue LED (OLED) chips not to emit light; thus, when the driving unit drives the light unit to output the visible light, the red LED (OLED) chips and the green LED (OLED) chips would emit the visible light with the specific wavelength ranging from 597 nm to 637 nm.

7. All the embodiment of the present invention can be added into a brightness switching unit for making the lighting device with switchable day/night illumination mode has the functionality for adjusting the intensity of the visible light outputted by the lighting unit; Therefore, for some people having reading habit before bed-time, they can use brightness switching unit to adjust the intensity of the visible light outputted by the lighting unit and use visible light with low intensity for assist in reading, so that, they can avoid from exciting their sympathetic and causing melatonin suppression.

The above description is made on embodiments of the present invention. However, the embodiments are not intended to limit scope of the present invention, and all equivalent implementations or alterations within the spirit of the present invention still fall within the scope of the present invention.

I claim:

1. A lighting device with switchable day/night illumination mode comprising:
  - a main controlling unit;
  - a driving unit, being coupled to the main controlling unit;
  - a lighting unit, being coupled to the driving unit and having a plurality of light-emitting devices, wherein the main controlling unit controls the driving unit to drive the lighting unit, so as to output a visible light;
  - a light filtering unit, being disposed over a light-emitting surface of the lighting unit, used for filtering the visible light and making the visible light become a visible light with a specific wavelength;
  - an illumination mode switching unit, being coupled to the main controlling unit, wherein the illumination mode switching unit is used for controlling and switching the light filtering unit, so that the light filtering unit shows and covers the light-emitting surface of the lighting unit, and then the visible light outputted from the lighting unit is filtered by the light filtering unit and becomes the visible light with the specific wavelength; moreover, the illumination mode switching unit is able to control and switch the light filtering unit, such that the light filtering unit is withdrawn and stops covering the light-emitting surface of the lighting unit, and then the lighting unit outputs the visible light; and
  - a power management unit, being coupled to the main controlling unit for providing the power to the main controlling unit.

12

2. The lighting device with switchable day/night illumination mode of claim 1, further comprising:

a switching unit, being coupled to the power management unit for switching the power management unit ON/OFF; and

a sensor unit, being coupled to the main controlling unit and the power management unit, used for detecting the light intensity of an external environment, wherein when night is coming, the sensor unit would output a first switch signal to the main controlling unit, and the main controlling unit would control the illumination mode switching unit to switch the light filtering unit to show and cover the light-emitting surface of the lighting unit; moreover, when day is coming, the sensor unit would output a second switch signal to the main controlling unit, and the main controlling unit would control the illumination mode switching unit to switch the light filtering unit to withdraw for stopping covering the light-emitting surface of the lighting unit.

3. The lighting device with switchable day/night illumination mode of claim 2, further comprising an activating unit, coupled to the sensor unit for activating the sensor unit to detect the light intensity of the environment.

4. The lighting device with switchable day/night illumination mode of claim 1, wherein the light-emitting device is selected from the group consisting of: bulb, fluorescent lamp, LED chip, and OLED chip.

5. The lighting device with switchable day/night illumination mode of claim 1, wherein the wavelength of the visible light with the specific wavelength ranging from 597 nm to 637 nm.

35 6. The lighting device with switchable day/night illumination mode of claim 1, wherein the power management unit is selected from the group consisting of: battery and power supply.

7. The lighting device with switchable day/night illumination mode of claim 1, further comprising a brightness switching unit, being coupled to the main controlling unit, wherein when the driving unit drives the lighting unit to output the visible light, the brightness switching unit may be used for adjusting the intensity of the visible light outputted by the lighting unit.

45 8. A lighting device with switchable day/night illumination mode comprising:

a main controlling unit;

a driving unit, being coupled to the main controlling unit;

a lighting unit, being coupled to the driving unit and having a plurality of light-emitting devices, wherein the main controlling unit controls the driving unit to drive the lighting unit, so as to output a visible light;

a light converting unit, being disposed over a light-emitting surface of the lighting unit, used for converting the visible light to a visible light with a specific wavelength;

55 an illumination mode switching unit, being coupled to the main controlling unit, wherein the illumination mode switching unit is used for controlling and switching the light converting unit, so that the light converting unit shows and covers the light-emitting surface of the lighting unit, and then the visible light outputted from the lighting unit is converted by the light converting unit and becomes the visible light with the specific wavelength; moreover, the illumination mode switching unit is able to control and switch the light converting unit, such that the light converting unit is withdrawn and stops covering the light-emitting surface of the lighting unit, and then the lighting unit outputs the visible light; and

13

a power management unit, being coupled to the main controlling unit for providing the power to the main controlling unit.

9. The lighting device with switchable day/night illumination mode of claim 8, further comprising:

a switching unit, being coupled to the power management unit for switching the power management unit ON/OFF; and

a sensor unit, being coupled to the main controlling unit and the power management unit, used for detecting the light intensity of an external environment, wherein when night is coming, the sensor unit would output a first switch signal to the main controlling unit, and the main controlling unit would control the illumination mode switching unit to switch the light filtering unit to show and cover the light-emitting surface of the lighting unit; moreover, when day is coming, the sensor unit would output a second switch signal to the main controlling unit, and the main controlling unit would control the illumination mode switching unit to switch the light filtering unit to withdraw for stopping covering the light-emitting surface of the lighting unit.

10. The lighting device with switchable day/night illumination mode of claim 9, further comprising an activating unit, coupled to the sensor unit for activating the sensor unit to detect the light intensity of the environment.

11. The lighting device with switchable day/night illumination mode of claim 8, wherein the light-emitting device is selected from the group consisting of: bulb, fluorescent lamp, LED chip, and OLED chip.

12. The lighting device with switchable day/night illumination mode of claim 8, wherein the wavelength of the visible light with the specific wavelength ranging from 597 nm to 637 nm.

13. The lighting device with switchable day/night illumination mode of claim 8, wherein the power management unit is selected from the group consisting of: battery and power supply.

14. The lighting device with switchable day/night illumination mode of claim 8, further comprising a brightness switching unit, being coupled to the main controlling unit, wherein when the driving unit drives the lighting unit to output the visible light, the brightness switching unit may be used for adjusting the intensity of the visible light outputted by the lighting unit.

15. A lighting device with switchable day/night illumination mode comprising:

a main controlling unit;
a driving unit, being coupled to the main controlling unit;
a lighting unit, being coupled to the driving unit and having a plurality of light-emitting devices, wherein the main controlling unit controls the driving unit to drive the lighting unit, so as to output a visible light;

a first switching unit, being coupled to the main controlling unit, wherein when the driving unit drives the lighting unit to output the visible light, the first switching unit is

14

used for controlling and adjusting the number of the plurality of light-emitting devices used for emitting light, or controlling some light-emitting devices in the plurality of light-emitting devices capable of emitting a visible light with a specific wavelength to emit light and controlling some light-emitting devices in the plurality of light-emitting devices incapable of emitting the visible light with the specific wavelength not to emit light; and

a power management unit, being coupled to the main controlling unit for providing the power to the main controlling unit.

16. The lighting device with switchable day/night illumination mode of claim 15, further comprising:

a switching unit, being coupled to the power management unit for switching the power management unit ON/OFF; a sensor unit, being coupled to the main controlling unit and the power management unit, used for detecting the light intensity of an external environment, wherein when night is coming, the sensor unit would output a first switch signal to the main controlling unit, and the main controlling unit would control the first switching unit to switch and adjust the number of the plurality of light-emitting devices used for emitting light, or control the some light-emitting devices in the plurality of light-emitting devices capable of emitting the visible light with the specific wavelength to emit light and control the some light-emitting devices in the plurality of light-emitting devices incapable of emitting the visible light with the specific wavelength not to emit light; and

an activating unit, coupled to the sensor unit for activating the sensor unit to detect the light intensity of the environment.

17. The lighting device with switchable day/night illumination mode of claim 15, wherein the light-emitting device is selected from the group consisting of: bulb, fluorescent lamp, LED chip, and OLED chip.

18. The lighting device with switchable day/night illumination mode of claim 15, wherein the wavelength of the visible light with the specific wavelength ranging from 597 nm to 637 nm.

19. The lighting device with switchable day/night illumination mode of claim 15, wherein the power management unit is selected from the group consisting of: battery and power supply.

20. The lighting device with switchable day/night illumination mode of claim 15, further comprising a second switching unit, being coupled to the main controlling unit, wherein when the driving unit drives the lighting unit to output the visible light, the second switching unit may be used for adjusting the intensity of the visible light outputted by the lighting unit.
